UNITED STATES PATENT OFFICE.

JOSEPH LEHIGH JENSEN AND NELS ARTHUR OLSON, OF COUNCIL BLUFFS, IOWA.

WALL CONSTRUCTION.

1,151,952.

Specification of Letters Patent. Patented Aug. 31, 1915.

Application filed June 5, 1914. Serial No. 843,257.

To all whom it may concern:

Be it known that we, JOSEPH LEHIGH JENSEN and NELS ARTHUR OLSON, citizens of the United States, residing at Council Bluffs, in the county of Pottawattamie, State of Iowa, have invented a new and useful Wall Construction, of which the following is a specification.

This invention relates to wall construction, one of the objects of the invention being to provide blocks of plastic material and which are of novel form so that, when the blocks are assembled, those blocks forming one course will interlock with the blocks forming the next adjoining courses, each course serving as a retaining means for the course thereunder, so that, when the blocks of one course are secured together, outward movement of the blocks of the next course thereunder is prevented.

A further object is to provide a wall construction utilizing tying means which is completely housed in the blocks and which serves to bind together the blocks of each course.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings: Figure 1 is a plan view of a curved wall made up of blocks such as constitute the present invention. Fig. 2 is a section on line A—B Fig. 1. Fig. 3 is a perspective view of one of the blocks.

Referring to the figures by characters of reference 1 designates a block of plastic material preferably formed with an opening 2 extending therethrough from one side to the other, one side of the block being preferably slightly concaved while the other side of the block is preferably slightly convex so that, when the blocks are assembled, they will fit one within another, as shown particularly in Fig. 1. The outer portion of the upper end of each block is removed to form a flat ledge 3 parallel with the end of the block, said ledge being overhung by an inclined shoulder 4 extending throughout the width

of the block. The inner portion of the lower end of each block is cut away so as to form an inclined shoulder 5 which is parallel with the overhanging shoulder 4, all of the upper and lower faces of the block being in parallel planes. Extending transversely through the lower end portion of the block is an opening 6 and, when a series of blocks are assembled, the openings 6 therein will register so that it is thus possible to thread a tie cable 7 or the like through the openings.

In erecting a wall a course of blocks 8 is placed on the foundation, these blocks 8 being similar to those hereinbefore described, with the exception that the lower ends thereof are not cut away. These blocks of the lower course are held together by inserting a tie device 7 through the registering openings 6. A second course of blocks is mounted on the blocks 8, the shoulders 5 of these blocks of the second course extending under the overhangs 4 on the blocks of the lower course. A tie 7 is then inserted through the openings 6 in the blocks of the second course and, when tightened, will not only draw the blocks 1 tightly together but will also bind shoulders 5 tightly against the overhangs 4. Consequently the upper ends of the blocks 8 will be prevented from pressing outwardly. The other courses are then placed in position in the manner hereinbefore described. Thus it will be seen that a wall is produced which is capable of resisting extreme outward pressures, each tie device being so placed as to constitute a reinforcing and tying means for the meeting portions of two courses of blocks. Furthermore the tie devices are completely concealed where they are not exposed to the weather. By using these tie devices and by forming the blocks with interfitting sides, it becomes unnecessary to employ cement or other means for filling in between the blocks.

What is claimed is:—

1. A wall construction made up of superposed courses of blocks, the blocks of one course having upwardly and outwardly inclined overhangs upon their upper ends and the blocks of the next adjoining course thereabove having a depending projection formed by downwardly and inwardly inclined shoulders extending outside of and under the overhangs there being an aperture extending through each projection, and a tie

device extending through said apertures and outside of the engaged portions of the blocks of the next adjoining course thereunder.

2. A wall construction consisting of a course of blocks, each block having its upper end formed with an outwardly and upwardly inclined shoulder, and an upper course of blocks resting upon said first mentioned course, each block of the upper course being provided with an inwardly inclined shoulder extending outside of and inwardly under the adjacent shoulder, there being registering openings within the shouldered portions of the blocks of the upper course,

and a tie device extending continuously through said registering openings whereby the shouldered portions of the blocks of the upper course are prevented from shifting outwardly from under the shoulders engaged thereby.

20

In testimony that we claim the foregoing as our own, we have hereto affixed our signatures in the presence of two witnesses.

JOSEPH LEHIGH JENSEN.
NELS ARTHUR OLSON.
